UNITED STATES PATENT OFFICE.

ALONZO F. HAVENS, OF BROOKLYN, NEW YORK.

IMPROVEMENT IN APPARATUS FOR CHARGING GAS-RETORTS.

Specification forming part of Letters Patent No. 140,624, dated July 8, 1873; application filed May 14, 1873.

To all whom it may concern:

Be it known that I, ALONZO F. HAVENS, of Brooklyn, in the county of Kings and State of New York, have invented an Improvement in Gas-Retort Chargers, of which the following is a specification:

Charging-scoops for gas-retorts have been made for delivering the contents into the retort by drawing aside a divided segmental bottom, as in my patent No. 134,055. My present invention is for accomplishing the same object, but by different mechanism, consisting of a bottom to the scoop made of two leaves hinged together in the middle, lengthwise of the scoop, and attached to arms that are employed for lifting up the central portion of the hinged bottom, so as to draw in the edges and allow the coal to be delivered off the leaves in their inclined positions toward the angles of the retort, so as to be more easily and evenly spread upon the bottom of the retort than in those cases where the coal is delivered in the center of the retort.

In the drawing, Figure 1 is a plan of the said charging apparatus. Fig. 2 shows the same sectionally, as in a retort, and containing the charge; and Fig. 3 is a section with the hinged bottom raised and the coal discharged.

The frame *a* is of suitable size, and either slides or runs upon wheels *b*. When in the retort this frame is supported by the bottom, and when out of the retort it rests upon suitable tracks or ways that can be moved along from one retort to the other. The tracks or ways may have rollers near the retort, upon which the frame *a* rolls. These devices do not require further description.

The casing of the charger is made of the sheet-metal sides *c*, united at their upper edges by the cross-bands *d*, so as to leave the necessary opening through which the coal is introduced. At their lower edges the sides *c* are connected to the frame *a* by means of pins *i* upon the frame *a* passing through slots in the sheet metal *c*, so that the frame *a* can be moved endwise slightly, or the casing *c* moved in the

frame *a* endwise. Upon the casing *c* or bands *d* are bearings *h* for the shaft *k*, that is provided with cranks *l* extending to the hinge-pins *o* of the hinges *r* that unite the leaves *s* of the folding bottom of the charger. The leaves of the folding bottom may be nearly the length of the retort, or in shorter sections. When the charger is in position for receiving the coal the ends of the folding bottom *s* rest upon a ledge, *u*, or part of the frame *a*, and also upon the pins *i*, and in this position the charger is inserted into the retort. The end of the frame *a*, coming into contact with the end of the retort or a stop, arrests the movement of said frame *a* and the further movement of *c* *d* and the parts connected therewith, cause the ends of the leaves *s* to pass off the ledge *u*, and brings the notches *t* that there are in the edges of such leaves over the pins *i*, so that the outer edges of the folding bottom drop, and, by partially revolving the shaft *k*, the folded bottom *s* is raised bodily into the position shown in Fig. 3, and the coal delivered upon the bottom.

There may be a crank-arm at the outer end of the shaft *k*, and a counter-weight, as illustrated by dotted lines in Figs. 2 and 3, so as to raise or aid in raising the folded bottom, or the shaft *k*, may be moved by any desired means.

As the charger is withdrawn from the retort the coal may be spread by a cross-bar at the back end of the frame *a*, and, as the movement is completed, the end motion is given either to the frame *a* or parts *c* *d* of the charger, so as to bring the ledge *u* below the ends of the folded bottom and open out the said bottom to its place as the shaft *k* is turned to lower said bottom. If the folding bottom is made in sections a cross-bar will be required to each to act in the same way as the ledge *u*. The pins *i* may be drawn back to drop the edges of the folding bottom, instead of using notches in *s* and an end movement.

The interior of the retort becomes coated with a scale that is difficult to remove. By placing rollers upon the case *c* and the rollers *b* so that they run in the angles of the re-

tort these parts will be kept free of scale, and the other portions of scale can be easily broken off, or will fall in the retort.

I claim as my invention—

1. The hinged folding bottom *s* and crank-arms upon the shaft *k*, in combination with the charger *c d*, substantially as set forth.

2. The frame *a* and ledge *u*, in combination with the hinged bottom and charger, the parts

being constructed and operating substantially as set forth.

Signed by me this 8th day of May, A. D. 1873.

ALONZO F. HAVENS.
